FIG. 2

FIG. 4

FIG. 1 is a front perspective view of a chair or similar article, showing my new design, the view being broken in the middle; the side panels and back panel are upholstered and there is an upholstered front rail;

FIG. 2 is a rear perspective view of the same, broken in the middle;

FIG. 3 is a front elevational view of a modified form of chair or similar article embodying my new design and differing from the chair or similar article of FIG. 1 in that the side panels and back panel are not upholstered;

FIG. 4 is a rear elevational view of the chair or similar article of FIG. 3, also broken in the middle;

FIG. 5 is a front perspective view of another modified form of chair or similar article embodying my new design, broken in the middle, and like the chair or similar article of FIG. 1, except that it does not have an exposed front rail.

I claim:

The ornamental design for a chair or similar article, substantially as shown and described:
